UNITED STATES PATENT OFFICE.

HIRAM C. GILBERT, OF BURLINGTON, VERMONT.

MACHINE FOR GRINDING SHIMER-MOLDING BITS, &c.

SPECIFICATION forming part of Letters Patent No. 400,660, dated April 2, 1889.

Application filed July 5, 1888. Serial No. 279,014. (No model.)

To all whom it may concern:

Be it known that I, HIRAM C. GILBERT, a citizen of the United States, residing at Burlington, in the county of Chittenden and State 5 of Vermont, have invented certain new and useful Improvements in Machines for Grinding Shimer Molding and Sash Heads and other Circular Bits of Matcher-Heads, of which the following is a specification, reference being 10 had therein to the accompanying drawing.

My invention relates to an improvement in sharpening-machines which are intended more especially for sharpening circular bits of matcher-heads; and it consists in the combination of a revolving emery-wheel, which is mounted in vertical adjustable bearings, an arbor upon which the matcher-head is placed to be sharpened, a frame through which the mandrel passes, a revolving block by which 20 the mandrel is adjusted vertically, a handle for horizontally revolving the adjusting-block, and a carriage by means of which the head is moved back and forth in relation to the emery-wheel, as will be more fully described 25 hereinafter.

The object of my invention is to provide a machine by means of which the circular bits of matcher-heads can be quickly and accurately sharpened, and all of those portions of 30 the circular bits which are upon the same plane or line can be alternately sharpened by simply revolving the head to which they are attached in relation to the emery-wheel.

The accompanying drawing represents a 35 perspective of a machine embodying my invention.

I represents a suitable carriage, which is adapted to be moved horizontally back and forth in relation to the emery-wheel B by 40 means of the hand-wheel W and the shaft to which the wheel is secured. The carriage I, which may be of any ordinary construction, and which has only an endwise movement, has mounted upon its top a suitable support, 45 upon the top of which is mounted the handle F, the adjusting-block D, and the mandrel-frame E. The mandrel-frame is made circular at its upper end, and passing horizontally through it is the mandrel A, which is provided with the hand-wheel C at one end, and

upon which the head H, carrying the rotary cutter, is placed. The shank of the frame E is made screw-threaded and passes down through the adjusting-block D, which is adapted to be revolved by means of a detachable handle, which is adapted to catch in the openings in its side, and thus raise or lower the frame E, carrying the mandrel A, and the head H, placed upon it. This block D rests upon the handle F, so that when the clamping-screw N is loosened the handle can be turned partially around, carrying the block, the frame, and the mandrel with it, thus adjusting the head H into any desired relation to the wheel B. The clamping-screw N passes 55 down through a slot in the support M, for the purpose of locking the handle F in any desired position, and the handle F can be moved horizontally around the length of this slot, and thus turning the mandrel and its frame 60 in any desired direction. Rising above the carriage at one side are the two standards P, each of which are made in two parts and the upper parts of which are vertically adjustable, so that the wheel B can be adjusted in 65 relation to the head H. This wheel is secured to a shaft, which is journaled upon the upper ends of the bearings P, and which is provided with a driving-pulley, S, at its center. The wheel B, having been adjusted in relation to 70 the bits, and the head having been turned into the desired position, all those portions of the bits which are upon the same circle can be sharpened alternately and with great rapidity 75 and the utmost precision. After one portion 80 of all the bits have been sharpened the head and wheel can be given any other adjustment necessary, and then the other portions of the cutting-edges of the bits also sharpened.

By means of the construction here shown 85 and described all of the difficulty of sharpening bits having uneven cutting-edges is entirely done away with. It is only necessary to place the head H upon the mandrel and then turn the mandrel into the desired position to properly present the bits to the wheel, and as fast as one bit has been sharpened 90 turn the mandrel so as to present another bit.

Having thus described my invention, I 95 claim—

1. The combination of a reciprocating carriage, a handle mounted thereon, and an adjusting-block placed upon the handle, the mandrel-frame having its shank to pass through the block, and the mandrel which passes through the frame and upon which the head is placed, substantially as described.

2. The combination of a vertically-adjustable emery-wheel, an adjustable mandrel upon which the head is placed, a frame through which the mandrel passes, an adjust-

ing-block by which the frame is adjusted vertically, a handle for turning the frame horizontally around, a locking-screw for holding the handle in any desired position, and a reciprocating carriage, substantially as set forth.

In testimony whereof I do affix my signature in presence of two witnesses.

IIIRAM C. GILBERT.
